UNITED STATES PATENT OFFICE

150,475

DESIGN FOR A MILK CART

Ray J. Swenson, Anoka, Minn.

Application June 11, 1947, Serial No. 139,579

Term of patent 7 years

(Cl. D14—3)

To all whom it may concern:

Be it known that I, Ray J. Swenson, a citizen of the United States, residing at Anoka, in the county of Anoka and State of Minnesota, have invented a new, original, and ornamental Design for a Milk Cart, of which the following is a specification, reference being had to the accompanying drawing, forming part thereof.

The figure is a perspective view of a milk cart, showing my new design.

I claim:

The ornamental design for a milk cart, as shown.

RAY J. SWENSON.
